John Weston, Alexandria (A. S.).

Seller's Patent

The schedule referred to and the Seller's Patent and making part of the same
containing a description of the mode of making the Weston's Improved
Improvement in the platform scale, or platform for weighing heavy bodies.

It all whom it may concern be it known, that John Weston of the town of Alexandria
in the County of Virginia and State of New York have made certain im-
provements in the machine for Weighing heavy bodies, and I hereby declare
that the following is a full, perfect and exact description of the machine as
improved, difference being due to the drawings which accompany this
specification, and make a part thereof. I also declare that in these drawings
and in this description I have represented and described many parts which
are common to other machines for the same purpose. These I have done for
the purpose of more clearly showing my improvement, wherein I claim to have
made improvements.

Fig. A. I. Represents the machine with the platform removed
showing the arrangement of the platform, base, &c. &c. is the base frame
of the machine, made of timber or other suitable materials. H. H. are two sets of
crooked, crooked, & open pieces of the machine on which the platform is hung
on. C. C. are arms of the middle beam, firmly attached to the crooked pieces, &c.
and standing in the center of the machine directly over the end of the main
balance beam. The arms of crooked, & acting parts of the middle beam are pro-
vided with knife-edged pieces of hardened steel call iron or other hard
(see Fig. 1) iron which knife-edged edges a double back, (see Fig. 2) roots and two
roots the arms of crooked to the end of the balance beam.

C. C. are crooked pieces of iron or other hard
steel timber or nucleus to which are fixed the knife-edged pieces &
hinges (see Fig. 3) C. C. are pieces of hardened steel cast iron or other hard
metal which are firmly fixed to the crooked pieces &c. forming where so joined
the necessary and part of the acting parts of the middle beam and are

partake with upper and lower knife edges, the lower of which rests in the flute of the swinging fulcrum or tail, forming the centre of the bias of the middle beam and the upper designed to receive and sustain the weight of the platform.

The upper and lower knife edges are on a horizontal beam with the knife edge on the side of the beam. G. G. are swinging fulcrum or tails having some circular grooves of flutes with which to rest the lower knife edge of that part of the middle beam, last above described having knife edges on each side, resting on standards. G. G. are standards made of hardened steel cast. Then on other hand, metal resting on and fixed to the cross pieces A.B. and having base plates or plates in the top with guards on the outer side which form fulcrum in which the knife edges of the swinging fulcrum or tails to rock (See Fig. 2 and 3 to the right in this plate) which give a swinging motion to the beam and cause the beam to accommodate themselves to the side and face of the platform without friction or scraping on the knife edges. A.M. are pieces of hardened steel cast when on other hand, metal, which are fastened to the acting ends of the beam having knife edges on which rock the connecting hooks A.B. a beam of oak or other suitable wood having knife edges pieces A.B. fastened to each of its ends a hook is attached to the exterior end of this beam, a loop working over the knife edge which is on the lower side from which a connecting rod of wrought iron reaches to the flat guards. The inner end is connected to the centre beam by means of a double hook which is made of steel and elastic and rocks over the lower knife edge A in the beam and the upper knife edges A.B. on beam, A.B.

A.B. a guigeon, made of hardened steel or cast iron and is fixed side and side to the centre of traction in the main beam lower & equivalent from its ends with knife edges on the upper side of each of its ends a rock in the ear pieces A.B. A.M. ear pieces of hardened steel cast. Then on other hand, metal which are fixed to the hanks A.C. C.D. receiving plates which the knife edges of the guigeon A. rock. A.B. ear pieces of pine or other timber described or otherwise fixed together forming a box around the apparatus.

Fig. 3. Represents the under side of the platform which are part of the frame work. A.B. are cross pieces, made of oak or other wood, all hanks. C.C.C. C.D. pieces of hardened steel, cast iron or other hard metal, having grooves of flutes with guards on the outer side which form fulcrum for this

the ship, except, excepting two of the middle standards. Fig 7 is a sketch of what is called the Brackets Weight, suspended by one and adapted to lay flat on a platform. It is made in the usual way of steel yards of that kind with a movable piece with notches and figures on the bar, but at the end it has a piece through the bar with knaps bags on the upper side of each end, over which a wooden block passes to which the heavy end is attached by means of a hook. for the suspension of weights. It is a smooth round rod of iron, "which is the end of the steel yard bar to which the ball is hinged. It is a ball of iron prepared with a hole of the size of the rod, & on which it slips with a blunt screw inserted through the side to the center of the ball and which fastens the ball when suspended to the rod. The object here is to lay in use of the rod and ball which attach to the steel yard, to form a counterpoise to the platform, preparing to weighing.

Common scale weights bearing a given ratio to each other are proposed to be placed in the ship &c. The steel yard being graduated with the mercantile piece to weigh any number of pounds from one to a hundred. The weight placed in the ship & being divided, see. for 100, 500, or 1000 or any other number of pounds. The mercantile piece will point out the number of pounds between the standards. These numbers are given only to explain the principle, and is applicable to weights of any required amount and may be graduated to any size desired.

Fig 8 is a perspective representation of the lower knife edge stings, &c. the lower knife edge of which joins the corner of the middle standards and works to the springing futtocks tail. & The upper edge serves to the futtocks, &c. Fig 9 and carries and sustains the weight of the platform.

Fig. 10 is a perspective representation of the knife edged H. H. by y. & a representation of the double block which connects the bars in the centre of the structure. Fig 11 is a perspective representation of the ear pieces & futtocks. Fig 12 is a perspective view of the springing futtocks & tail showing the manner in which they rest on the standards. Fig 13 is a perspective representation of one of the standards showing the level plate or plate to which the knife edge of the springing bars or futtocks are designed to rest.

The construction of a standard, & a weighing counterpoise are usually constructed in such a manner in the arrangement of the lower deck.

that the balance is so low down which is made from the uprights or centre beam being
so narrow, and to the side by so closing, retaining, the same principles and na-
ture of the lever.

The machine as constructed for store may be either posted
or let into the floor, that the platform will be level therewith and the balance
lever may be lengthened or shortened, without altering the graduation of the
steel yard by so closing, I am enabled to attack the steel yard, to the end of
the balance lever at any distance from the platform and in any position
that may be required retaining the same graduation of the balance lever
when lengthened or shortened & attack the steel yard.

What I claim is an improvement upon the straighting ma-
chines, more in size & the variation in the manner of arranging and con-
necting together the lever as shown in Figures 1 and 2 giving the acting part
of the machine in a power of motion which are upon the first trial of their
purchase, I also claim the variation in the manner of arranging the
straighting machine in fact resting upon standards as shown in Fig 1 which
imparts a vibratory or straighting motion in the supporting frame by means
of said standards more easily. I also claim the manner of fixing and pla-
cing the machine between two by means of which the frame is conveniently
rested upon the floor yard bed by means of its connection to the frame
bed with the centre hook as shown in figure 2. (Form 2 fig 2). I also
claim upon the steel yard by the manner in which I connect the graduated weight
at the end by means of the pin through the end of the bar and the hook, so as to rest
upon its knif edge & which the hook is attached for the reception of the weight at the
manner of connecting the platform & being it into equilibrium preparatory to
straighting by the means of the smooth rod attached to the extremity of the steel yard
bar, and the perforated ball with the hemis. screw through its side which is made to
slide on said rod to protect the pin from balance (See Fig 4) not interesting however
by these claims I consider myself to be exact from and manner of constructing the
earlier part of my machine as herein exemplified but to vary the same, as being
first concerned in any way which produces similar effects upon the same prin-
ciples, modes of action.

In testimony that the foregoing is a true Specification
